CLAIM

The ornamental design for an article of furniture, as shown and described.

DESCRIPTION

FIG. 1 is a rear perspective view of a first embodiment of an article of furniture showing our new design with a cushion being shown in a first position;

FIG. 2 is a front perspective view thereof;

FIG. 3 is a top plan view thereof;

FIG. 4 is a front view thereof;

FIG. 5 is a right side view thereof, the left side view being a mirror image thereof;

FIG. 6 is a rear view thereof;

FIG. 7 is a rear perspective view of the article of furniture of FIGS. 1-6 with the cushion being shown in a second position;

FIG. 8 is a front perspective view thereof;

FIG. 9 is a top plan view thereof;

FIG. 10 is a front view thereof;

FIG. 11 is a right side view thereof, the left side view being a mirror image thereof;

FIG. 12 is a rear view thereof;

FIG. 13 is a rear perspective view of a second embodiment of an article of furniture with a cushion being shown in a first position;

FIG. 14 is a front perspective view thereof;

FIG. 15 is a top plan view thereof;

FIG. 16 is a front view thereof;

FIG. 17 is a right side view thereof, the left side view being a mirror image of FIG. 5;

(Continued)

FIG. 18 is a rear view thereof;
 FIG. 19 is a rear perspective view of the article of furniture of FIGS. 13-18 with the cushion being shown in a second position;
 FIG. 20 is a front perspective view thereof;
 FIG. 21 is a top plan view thereof;
 FIG. 22 is a front view thereof;
 FIG. 23 is a right side view thereof, the left side view being a mirror image of FIG. 11;
 FIG. 24 is a rear view;
 FIG. 25 is a rear perspective view of a third embodiment of an article of furniture with a cushion being shown in a first position;
 FIG. 26 is a front perspective view thereof;
 FIG. 27 is a top plan view thereof;
 FIG. 28 is a front view thereof;
 FIG. 29 is a right side view thereof, the left side view being a mirror image thereof;
 FIG. 30 is a rear view thereof;
 FIG. 31 is a rear perspective view of FIGS. 25-30 with the cushion being shown in a second position;
 FIG. 32 is a front perspective view thereof;
 FIG. 33 is a top plan view thereof;
 FIG. 34 is a front view thereof;
 FIG. 35 is a right side view thereof, the left side view being a mirror image thereof; and,
 FIG. 36 is a rear view thereof.
 The broken lines illustrate portions of the article of furniture, that form no part of the claimed design.
